UNITED STATES PATENT OFFICE.

WILLIAM D. BAYLEY, OF SPRINGFIELD, OHIO.

SILO.

Application filed June 1, 1925. Serial No. 34,002.

This invention relates to silos, it particularly relating to silo doors, the reinforcement of the door frames, means for supporting the chute and the ladder construction.

5 One of the objects of the invention is to provide for so forming and supporting the doors as to insure a tight closing of the doors.

10 Another object of the invention is to provide a reinforcement for the door frame so arranged as to utilize a portion of the bolts or other fastening devices which secure the silo sections together to also secure the reinforcement.

15 Another object of the invention is to provide improved means for supporting the chute through which the material in the silo is discharged.

20 Another object of the invention is to improve the construction of the ladder whereby certain of the rungs of the ladder may be readily swung to a vertical position clear of the doorways.

25 Other objects of the invention will appear from the accompanying description.

In the accompanying drawings:

Fig. 1 is a side elevation of a portion of a silo showing one of its doors and a portion of the ladder, the chute being shown in section in this figure.

30 Fig. 2 is a section on the line 2—2 of Fig. 1.

Fig. 3 is a section on the line 3—3 of Fig. 1.

35 Fig. 4 is an enlarged sectional view of the parts shown in Fig. 3 showing a slight modification.

40 Fig. 5 is an elevation on a reduced scale of the inner side of the door and a portion of the metallic sheet against which the door seats, showing a modification in the form of the door opening in the sheet.

45 Referring to the drawings, 1 represents a series of curved silo sections of sheet metal having their side edges formed with out-turned lateral flanges 2 bolted together as shown in Fig. 1 and their top and bottom edges formed with lateral out-turned flanges 3 likewise bolted together by bolts 4 as shown in Fig. 3: the bottom flange of each section being formed with a down-turned flange 3' to provide a weather shield and lend strength. These same bolts 4 likewise secure in position a channel-shaped reinforcing member 5 by passing the bolts through the upper flange 5' thereof. The

same bolts 4 also secure in position brackets 6 which project outwardly from the silo structure and have bolted or otherwise secured thereto side members 7 of a ladder. 60

One of the sheet metal sections 1 shown in the drawings has its central portion cut away to form a door opening. In Fig. 1 this opening is shown formed with squared corners, but I prefer to make the corners rounding as indicated at 1' in Fig. 5 as this leaves more metal in the sheet, which, together with the shape, adds strength. The reinforcement member 5 extends along the upper edge of the door opening on the outer side of the 70 metallic sheet and in addition to this reinforcing member 5 the outer surface of each doorway is reinforced by a second channel-shaped reinforcing member 8 along the bottom thereof and by channel-shaped members 9 and 10 adjacent the sides. While in the drawings but one door opening is shown it will be understood that the silo is equipped with a series of door openings one above another. If desired, in the silo construction 75 described, a door opening may be placed in each ring of sheets and in that event the lower channel-shaped reinforcing member 8 will be attached to the outturned flanges 3 by the same fastening devices that connect the upper reinforcing member 5 of the doorway next below it as indicated in Fig. 4.

To the outer flanges 9' and 10' of the side reinforcement members there is secured the inner vertical edges of a U-shaped chute 11, a portion of the walls thereof being reinforced by members 12. Brackets 13, secured respectively to the chute walls and to the ladder sides 7 serve to further support the chute. 85

90 The door is formed of sheet metal and is indicated at 14, the door being reinforced in a vertical direction only by V-shaped metal members 15 having integral vertical side flanges 15' riveted to the door. The door is hinged to a vertical rod 16 which is supported in the eyes of straps 17 bolted or otherwise secured to the silo section 1 at the point where the reinforcing member 9 is applied thereto, the lower end of this rod 16 resting upon the upper flange 8' of the reinforcing member 8. The hinges, which are two in number, are each formed of a metallic strap, the intermediate portion 18 of which is preferably formed on the arc of a circle whose center is the longitudinal axis of the hinged rod 16. One end 95

105

100

110

115

of the strap is formed with an eye 19 which receives the rod 16 and between the eye and the curved portion 18 the strap is formed on straight lines as indicated at 20 of a 5 length equal to the distance between the rod 16 and the inner edge of the doorway. The other end of the strap is formed with a straight bent portion 21 secured to the door by the rivets 22. From Fig. 2 it will be 10 seen that the door is formed transversely on the arc of a circle of shorter radius than the arcs upon which the curves of the sections 1 of the silo walls are formed and it will also be noted that the free edge 14' of 15 the door is bent slightly outward so that when the doors close the edge 14' will strike the door frame slightly ahead of the adjacent portions of the upper and lower edges of the door, but practically simultaneously 20 with the inner edge of the door. The door is equipped with four clamps two near the lower edge and two near the upper edge. Each clamp consists of a plate 23 having a vertical slot 24 to receive a stud 25 which 25 is secured firmly to the door and is threaded to receive a wing-nut 26. The lower end of the clamp 23 is bent at right-angles outwardly as indicated at 27 and thence downwardly or upwardly, as indicated at 28, to 30 form a hook. These hooks engage the lower flange 5" and upper flange 8', respectively, of the reinforcing members 5 and 8. After the door has been closed sufficiently to cause the forward and rear edges and parts of 35 the upper and lower edges to make contact with the doorway, the entire door is sprung in against the door frame by pulling the handle 29 so that the hooks 28 may be placed over the legs 5" and 8', after which, by 40 manipulating the thumb-nuts 27, all of the edges of the door may be firmly clamped to the door frame, making a tight joint about the entire doorway. The peculiar construction of the hinges insures the inner 45 edge of the door being set firmly against the door frame and by bending the free edge of the door as indicated at 14' this insures that edge of the door being seated slightly in advance of the adjacent portion of the 50 top and bottom edges so that it will remain seated after the top and bottom edges have been drawn to position by the clamps, it being understood that the bent edge 14' will spring into alignment with the adjacent portion of the door under the pressure exerted by the clamp, and that the entire door will 55 assume the same curvature as that of the sections 1.

As shown in Fig. 1, that rung 30 of the 60 ladder which stands in front of the door is pivoted to one of the side members by the pivot pin 31". The vertical leg of the rung, which is preferably of angle-iron construction, at its other end rests in a pocket 65 formed by the out-turned upper end 31' of

a strap 31 which is secured to the other ladder member 7. This permits this rung of the ladder to be swung clear of the doorway when it is desired to discharge ensilage through the door. 70

By having the hinge rod 16 extend the full length of the door frame in connection with the three straps secured to the frame, the frame at that point is further stiffened and braced against the pressure of the ensilage. 75

Having thus described my invention, I claim:

1. In a door structure for silos, a curved door frame, a flexible door formed on a 80 shorter curve than said door frame, means for hinging the inner edges of said door to said frame, the outer edge of said door being slightly bent toward said frame, and means for drawing the edges of said door against 85 said frame and locking the same in that position.

2. In a door structure for silos, a curved door frame, an inwardly swinging sheet metal door formed on a shorter curve than said 90 frame, hinges secured to the outer side of said door near the inner edge thereof and also pivoted to the outer side of said door frame to permit the inner edge of said door to seat closely against the inner side of said frame, the outer edge of said door being bent slightly toward said frame, and clamping devices on said door and engageable with said door frame to draw the edges of said door in tight engagement with said frame. 100

3. In a door structure for silos, a curved door frame, a hinged inwardly swinging sheet metal door formed on a shorter curve than the door frame with its free edges bent towards the frame, curved hinge straps having one end secured to the outer side of said door near the inner edge thereof and the other ends pivoted to the outside of said door frame, a series of clamping devices on said door, each formed with a hook to engage said door frame and means for tightening the same to draw the edges of said door in tight engagement with said door frame and lock the same in that position. 105

4. In a structure of the character described formed of sheets of metal united at their edges, a door frame formed in one of said sheets by cutting a suitable shaped opening in the sheet leaving margins surrounding said opening, reinforcing members connected with the outsides of said marginal portions of said sheet, and an inwardly opening door larger than the opening so as to seat against the inner surfaces of the marginal portions of said sheet. 115

5. In a structure of the character described formed of sheets of metal united at their edges, a door frame formed in one of said sheets by cutting an opening in the sheet leaving marginal portions surrounding 130

said opening, reinforcing members connected with the outer surfaces of said marginal portions, an inwardly opening door larger than said opening and arranged to seat against the inner surfaces of said marginal portions of said sheet, hinges for said door connected with the outer side of one of the marginal

portions of said sheet and its reinforcing member, and fastening devices for said door engaging the upper and lower reinforcing ¹⁰ members.

In testimony whereof, I have hereunto set my hand this 23rd day of May, 1925.

WILLIAM D. BAYLEY.
